UNITED STATES PATENT OFFICE.

OSCAR JUNGGREN, OF SCHENECTADY, NEW YORK, ASSIGNOR TO GENERAL ELECTRIC COMPANY, A CORPORATION OF NEW YORK.

TURBINE WHICH UTILIZES GASES FROM FIRE-CHAMBERS FOR REHEATING.

No. 829,791.

Specification of Letters Patent.

Patented Aug. 28, 1906.

Application filed February 23, 1904. Serial No. 194,724.

To all whom it may concern:

Be it known that I, OSCAR JUNGGREN, a citizen of the United States, residing at Schenectady, county of Schenectady, State of New York, have invented certain new and useful Improvements in means for improving the efficiency of elastic-fluid turbines by reheaters which utilize the gases from fire-chambers, of which the following is a specification.

The present invention relates to elastic-fluid turbines, and has for its object to improve their efficiency by reheating the motive fluid in its passage through the turbine by means of the gases from a fire-chamber.

Tests made with different kinds of fuel, boilers, grate-surfaces, &c., show a considerable variation in the temperature of the flue-gases or waste products of combustion issuing from the fire-chamber; but in all cases they are considerably above that of the steam drawn from the boiler. The temperature of the flue-gases is also to a certain extent governed by the draft required to produce good combustion. I take advantage of this difference in temperature to reheat the steam or other motive fluid by causing the waste flue-gases to give up a certain amount of their heat on their way to the chimney to one or more reheaters. After the steam has passed through a nozzle or other discharging device its temperature is reduced by a greater or less amount, depending upon the ratio of expansion of the nozzle or device, and the greater the expansion the greater will be the difference in temperature between it and the escaping gases. By properly constructing and arranging the reheater or reheaters they can be made to absorb considerable heat from the gases without seriously affecting the draft, and therefore every degree that the temperature of the steam within the turbine is raised results in a gain, not only in the turbine itself, but in the system as a whole. The more directly the heat from the gases can be applied to the expanded steam the greater will be the saving.

In carrying out my invention a turbine of any desired construction may be provided, but preferably one in which the energy from the motive fluid is abstracted by successive stages. For the purpose of illustration I

have shown my invention in connection with a Curtis type of multistage turbine. Each stage of the turbine is provided with one or more nozzles, each composed of one or more fluid-carrying passages having a constant ratio of expansion which discharge the motive fluid at the proper angle against one or more rows of bucket-wheels. The several stages may be of similar or dissimilar construction, as best suits the conditions for which the machine is intended.

In addition to the above a reheater is provided for reheating the motive fluid as it passes through the turbine. I may surround the turbine-casing by a chambered jacket forming an external reheater or the diaphragm or separator employed to divide the turbine into stages may be formed with one or more heating-chambers forming internal reheating devices. A simple construction comprises a cast-metal diaphragm between wheels made in one or more pieces, each containing a chamber or chambers which is formed by a core at the time the casting is formed, or the diaphragms or separators may be made of separate pieces and suitably united.

The diaphragm or diaphragms are provided with one or more orifices leading into the chamber or chambers from the fire-chamber, and one or more orifices leading from the chamber or chambers to the chimney or stack. The path of the fire-gases through the diaphragms may be straight or tortuous, as best suits the requirements. The nozzle or nozzles, each containing one or more fluid-carrying passages, are preferably formed in the diaphragms so that the heat from the reheaters is readily imparted to the steam. I may use either or both of the arrangements specified; depending upon the character of the turbine and the degree of reheating desired. Between the point of exit of the gases from the fire-chamber of a vapor-generator or other apparatus and the reheating chamber or chambers is a flue of sufficient size to convey the gases without undue restriction, and between the chamber or chambers and the chimney or stack is a second flue, also of sufficient size to convey said gases without undue restriction.

It will be found to be satisfactory to utilize

the waste flue-gases from the fire-chamber which supplies the heat to the vapor-generator, that in turn supplies vapor to the turbine; but I may utilize the waste gases from 5 a different vapor-generator or from a superheater.

It is preferable to utilize the heat which is commonly wasted for improving the efficiency of the turbine; but under certain conditions I may supply fire-gases directly for reheating as distinguished from waste flue-gases, since the construction described is well adapted for such purposes. In the latter case care must be exercised not to overheat 15 the turbine parts or to apply the heat in such manner that it will cause distortion.

In the accompanying drawings, which illustrate one embodiment of my invention, Figure 1 is a plan view of a part of a power-station. Fig. 2 is a partial vertical section of a vertical-shaft turbine; and Fig. 3 is a sectional detail showing the relation of the nozzle to the other parts of the machine.

1 and 2 represent the walls of the building 25 containing the turbine, 3 the masonry foundation for the boiler and grate, and 4 the fire-chamber. (Shown in dotted lines.)

5 represents a vertical-shaft steam-turbine, and 6 an electric generator or other load therefor.

7 and 8 represent the steam-chests which receive steam from the supply-pipe 9, the latter being provided with a suitable throttle-valve 10, situated between the turbine and the boiler 11. Surrounding the turbine is a cylindrical jacket 12, containing a reheating-chamber 13, one of the main walls of the chamber being formed by the jacket and the other by the turbine-casing. Between the 40 fire-chamber and the reheating-chamber extends a flue 14, and between said chamber and the chimney or stack extends a flue 16. These flues are both provided with the necessary flanges, so that they can be coupled or uncoupled, as desired. The casing is made up in the necessary sections, so that it can be applied to and taken off from the turbine.

Referring to Fig. 2, 17 represents the base of the turbine, having a flanged neck 18, which 50 is connected to the condenser or other exhaust. Mounted above the base is a wheel-casing made up of cylindrical members 19, which are separated one from the other by diaphragms 20. These diaphragms are provided with top and bottom shoulders which engage with the portions of the casing and serve to center them. The diaphragms each contain one or more chambers 21, and the latter receive the fire-gases from the inlet-flue through one or more orifices 22 and discharge them through one or more orifices 23 into the discharge-flue 16. In order to cause the fire-gases to follow a more or less

tortuous path in passing through the chambers in the diaphragms or internal reheaters, 65 bafflers 24 25 are provided. The external reheater or jacket 12 is arranged to include all of the stages except the last, which is connected to the condenser. The jacket may with advantage be provided with a covering 70 of heat-insulating material.

Mounted in the turbine is a shaft 26, on which the wheels 27 are mounted. Each of the wheels is provided with one or more rows of wheel-buckets 28, which receive steam 75 or other elastic fluid from the nozzle formed in the diaphragm. Where one or more rows of wheel-buckets are provided, a row of intermediate buckets 30 is provided between them. The arc covered by the intermediate 80 buckets varies with the different stages, it being smallest in the first stage and greatest in the last stage. Steam is supplied to the nozzles of the first stage from the steam-chest 8, which contains suitable valves for 85 controlling the passage of fluid. To the steam-chest is connected a supply-conduit 9.

In accordance with the provisions of the patent statutes I have described the principle of operation of my invention, together 90 with the apparatus which I now consider to represent the best embodiment thereof; but I desire to have it understood that the apparatus shown is only illustrative and that the invention can be carried out by other 95 means.

What I claim as new, and desire to secure by Letters Patent of the United States, is—

1. An elastic-fluid turbine comprising a casing, a nozzle or fluid discharging device 100 and a wheel-bucket against which motive fluid is discharged, in combination with a reheating device carried by the turbine for heating the walls of the latter, and a flue for conveying fire-gases to the reheating device. 105

2. An elastic-fluid turbine comprising a casing, a nozzle or fluid discharging device, and wheel-buckets against which the motive fluid is discharged, in combination with a reheating device which heats the walls of 110 the casing and the fluid flowing through the nozzles and buckets, said device comprising in part a portion of the turbine and in part an independent structure, a fire-chamber, and a flue for conveying fire-gases from the 115 fire-chamber to the reheating device.

3. An elastic-fluid turbine comprising a casing, a nozzle or fluid discharging device, and wheel-buckets against which the motive fluid is discharged, in combination with a reheating-chamber formed in the turbine-walls, 120 a fire-chamber, and a flue arranged to receive fire-gases from the fire-chamber and discharge them into the reheating-chamber.

4. An elastic-fluid turbine comprising a 125 casing, a nozzle or fluid discharging device,

and wheel-buckets against which the motive fluid is discharged, in combination with a reheating device located at the turbine for heating its walls, said device comprising a wall surrounding and closely conforming to the shape of the casing and having an inlet and outlet at diametrically opposite points, a fire-chamber, a stack or chimney, a flue for receiving fire-gases from the chamber and discharging them in a manner to raise the temperature of the reheat, and a second flue for discharging the flue-gases into the stack after they have given up heat to the reheat.

15 5. An elastic-fluid turbine comprising a casing, a bucket-wheel, and a nozzle for discharging fluid against the bucket-wheel, which has a constant ratio of expansion, in combination with a reheating-chamber having one or more walls in common with the turbine and another wall carried thereby for increasing the temperature of the motive fluid as it flows through the nozzle and buckets, a fire-chamber, a flue for conveying the waste products of combustion from the fire-chamber to the reheating-chamber, a stack or chimney, and a flue for conveying the said products of combustion to the stack after they have given up a certain portion 30 of their heat in the reheating-chamber.

6. An elastic-fluid turbine comprising a casing for a wheel-chamber and a reheating-chamber entirely separate from the wheel-chamber, a nozzle or fluid discharging device, a wheel-bucket in the first chamber against which the motive fluid is discharged, in combination with a reheating-jacket which surrounds the cylindrical wall of the casing and communicates with the reheating-chamber in the latter, and a flue for conveying flue-gases to and from the jacket and reheating-chamber.

7. An elastic-fluid turbine comprising a casing which is divided into stages or compartments, a row of wheel-buckets in each compartment, and a nozzle or device for discharging motive fluid to the buckets of each stage, in combination with a reheating-jacket which surrounds two or more stages arranged to heat the motive fluid while passing from one stage to the next and while doing work in the stages, and flues for conveying waste flue-gases to and from the chamber in the jacket.

55 8. An elastic-fluid turbine which is divided into stages or compartments, one or more rows of wheel-buckets for each stage, a nozzle or discharging device for each stage, in combination with a reheating device which surrounds all of the stages except the last, and means connected with a fire-chamber for supplying fire-gases to the reheating device.

9. An elastic-fluid turbine comprising a casing, a plurality of wheels, and nozzles or devices for discharging motive fluid to the several wheels, in combination with chambered diaphragms situated between the wheels which divide the casing into compartments and form an internal reheat, a 70 reheater for the casing located exterior thereto, and a source of heat-supply common to the reheaters.

10. An elastic-fluid turbine comprising a casing, a plurality of wheels, and nozzles or devices for discharging motive fluid to the several wheels, in combination with a chambered diaphragm situated between the wheels, which divides the casing into compartments and across the chamber of which 80 nozzles extend, and means for supplying heat to a chamber in the diaphragm to heat the walls of the latter and also of the nozzles in the chamber for reheating the motive fluid.

11. An elastic-fluid turbine comprising a casing, a plurality of wheels, and nozzles or devices for discharging motive fluid to the several wheels, in combination with a chambered diaphragm between the wheels, which 90 divides the casing into compartments, and is provided with orifices opening into and out of the chamber, and a jacket forming with the casing a heating-chamber which communicates with the chamber of the diaphragm through the orifices.

12. An elastic-fluid turbine comprising a casing, a plurality of wheels, and nozzles or devices for discharging motive fluid to the several wheels, in combination with internal 100 and external means acting to convey flue-gases for reheating the motive fluid as it passes through the turbine.

13. An elastic-fluid turbine comprising a casing, a plurality of wheels, and nozzles or 105 devices for discharging motive fluid to the several wheels, in combination with internal and external heating-chambers which in common receive flue-gases for reheating the motive fluid as it passes through the turbine.

14. An elastic-fluid turbine comprising a casing, a plurality of wheels, and nozzles or devices for discharging motive fluid to the several wheels, in combination with a chambered diaphragm which divides the turbine into stages and is open to permit flue-gases to pass therethrough for internally heating two stages at the same time, and a chamber which receives flue-gases for heating the 115 turbine externally.

15. An elastic-fluid turbine comprising a casing, a plurality of wheels, and nozzles or devices for discharging motive fluid to the several wheels, in combination with internal 120 and external heating-chambers for reheating

the motive fluid as it passes through the turbine, and a conduit for conveying flue-gases which is common to the chambers.

16. An elastic-fluid turbine comprising a
5 casing, a plurality of wheels, and nozzles or
devices for discharging motive fluid to the
several wheels, in combination with internal
and external heating-chambers for reheating
the motive fluid as it passes through the tur-

bine, a source of heat which is common to the chambers, and flues for conveying flue-gases to and from the chambers.

In witness whereof I have hereunto set my hand this 20th day of February, 1904.

OSCAR JUNGGREN.
